(57) **CLAIM**

The ornamental design for a device for surgical decompression of branch retinal vein occlusion via microvascular arteriovenous adventitial sheathotomy, as shown and described.

DESCRIPTION

FIG. 1 is a left side elevational view of the device for surgical decompression of branch retinal vein occlusion via microvascular arteriovenous adventitial sheathotomy showing our new design, the right side elevational view being a mirror image thereof;

FIG. 2 is an enlarged fragmentary left side elevational view of the tip portion thereof;

FIG. 3 is a bottom plan view thereof, of FIG. 1;

FIG. 4 is an enlarged fragmentary top plan view of the tip portion thereof, of FIG. 2

FIG. 5 is an enlarged fragmentary top plan view of the tip portion thereof, of FIG. 2

FIG. 6 is a front elevational view thereof, of FIG. 1;

FIG. 7 is a rear elevational view thereof; and,

FIG. 8 is a top plan view thereof.
